UNITED STATES PATENT OFFICE.

JOHN E. SHAW, OF MURPHEYS, CALIFORNIA.

DRILL-SUPPORTING STRUCTURE.

Application filed March 3, 1926. Serial No. 91,911.

This invention relates to improvements in devices used to support rock drills of a certain standard type, when drilling in drifts, tunnels and the like.

Such drills, especially those known as the burley drill, are now supported by means of a vertical machine bar, extending between and held rigidly to the ceiling and floor of the drift, and a horizontal arm which projects outwardly from the bar and on which the drill is supported. This arm is detachably and adjustably mounted on the bar by clamps of such character that it is very hard to keep the arm from turning with the back pressure of the drill, and very large heavy wrenches are necessary to exert sufficient force against the clamping bolts to maintain the clamps tight.

The principal object of my invention is to provide a drill supporting structure, including a machine bar and the side arm, and connections between the arm and bar such that the arm is very easily adjusted in its radial setting without the need of any tools, and the vertical position of the arm is readily and quickly altered, while at the same time the arm cannot possibly turn relative to the bar.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a side elevation of the structure.

Fig. 2 is an enlarged section of the arm supporting member with the arm in position thereon.

Fig. 3 is a sectional plan on the line 3—3 of Fig. 2 with the arm removed.

Fig. 4 is a detached view of the drill supporting arm.

Referring now more particularly to the characters of reference on the drawings, the numeral 1 denotes the machine bar having at its opposite ends enlarged pads 2, one pad being provided with a screw jack structure 3 as is customary, to enable the pads to be firmly abutted against floor and ceiling beams. Slidable on the bar is a member to

support the horizontal drill supporting arm 4. This member comprises a central hub 5 connecting vertically spaced and somewhat wide flanges 6 and 7. The bar 1 may be squared, hexagonal, circular with a key-way or with a flattened surface, or of any other form; the only requirement being that the hub 5 while slidable on the bar cannot turn thereon. The upper flange 6 has an endless circular groove 8 projecting upwardly from its under face. This groove receives a rounded boss 9 formed on the adjacent end of the arm 4 and extending at right angles thereto. The arm at said end is square or rectangular in cross section as shown at 10, the height of this portion being about equal to the spacing between the flanges 6 and 7. To enable the boss 9 to be inserted into the groove 8 at any point without spreading the flanges (which are preferably formed integral with the hub 5) the under face of the portion 10 tapers upwardly to its end as shown. This permits the arm to be raised at its outer end sufficiently to cause the boss 9 to be lowered clear of the groove 8, when the arm may be drawn outwardly. At the same time it will be seen that the arm cannot swing beyond a horizontal position, nor can it be drawn straight out.

To hold the arm radial with the bar 1 the flanges 6 and 7 are provided with a plurality of pairs of radial and vertically aligned holes 11, one hole of each pair in the flange 6 being located in the plane of the groove 8, and the other hole being outwardly of said groove. The portion 10 of the arm 4 is drilled with holes to register with any pair of the flange holes, so that removable pins 12 may be placed through the flange and arm holes. It will therefore be seen that the arm cannot move laterally in the flange member without shearing the pins, and the flange member cannot turn on the bar. At the same time the removal of the pins enables the arm to be readily removed from any position and as quickly located in any position.

The flange member is held at any desired position on the bar 1 by a clamping collar 13 disposed about the bar under said member. This collar does not need to be very heavy since there is practically no downward pressure on the same, other than the weight of the flange member itself, since the weight of the drill supported by the arm is imparted

2 to the hub 5 as a pressure tending to bind the same against the bar rather than to force it down.

From the foregoing description it will be 5 readily seen that I have produced such a device as substantially fulfills the objects of the invention as set forth herein.

While this specification sets forth in detail the present and preferred construction 10 of the device, still in practice such deviations from such detail may be resorted to as do not form a departure from the spirit of the invention, as defined by the appended claims.

15 Having thus described my invention what I claim as new and useful and desire to secure by Letters Patent is:

1. A drill supporting structure comprising a vertical bar adapted to be maintained 20 in a fixed position, an arm to support a drill, a member slidably but non-turnably mounted on the bar, means between said member and the arm for removably supporting the latter in a horizontal position, said member 25 including flanges spaced apart vertically a

distance sufficient to receive one end of the arm therebetween, an upwardly projecting boss on said end of the arm, the under face of the upper flange being recessed all around to seat said boss in a number of different positions, and means between said arm and flanges to prevent lateral swinging movement of the arm.

2. A drill supporting structure comprising- 35 a vertical bar adapted to be maintained in a fixed position, an arm to support a drill, a member slidably but non-turnably mounted on the bar, means between said member and the arm for removably supporting the latter in a horizontal position, said member 40 including flanges spaced apart vertically a distance sufficient to receive one end of the arm therebetween, an upwardly projecting boss on said end of the arm, seating means for the boss in the upper flange, 45 the arm and flanges having alined orifices therethrough, and removable pins through said orifices.

In testimony whereof I affix my signature.
JOHN E. SHAW.
